UNITED STATES PATENT OFFICE.

HARRY W. HARDINGE, OF NEW YORK, N. Y., ASSIGNOR TO HARDINGE COMPANY, INC.,
OF NEW YORK, N. Y., A CORPORATION OF NEW YORK.

OUTLET FOR CONICAL MILLS.

Application filed October 7, 1921. Serial No. 505,968.

To all whom it may concern:

Be it known that I, HARRY W. HARDINGE, a citizen of the United States of America, residing at New York, in the county and 5 State of New York, have invented certain new and useful Improvements in Outlets for Conical Mills, of which the following is a full, clear, and exact description.

The invention which constitutes the subject matter of this application relates to 10 grinding mills. More specifically it relates to grinding mills of the type now known in the art as conical mills, i. e. mills in which a conical outlet portion automatically classifies the material, being disintegrated, according to size.

A type of grinding mill heretofore invented by me comprises a rotatable drum having an inlet trunnion, or other suitable 20 means, through which material to be disintegrated may be fed into the drum while the latter is rotating; a conical outlet portion for automatically classifying the material according to size; and an outlet trunnion 25 through which the fines are discharged by the rotation of the mill. One of the principal objects of the present invention is to improve the efficiency of such mills. Other objects and advantages will appear as the 30 invention is hereinafter disclosed.

Referring to the drawings which illustrate, what I now consider, preferred forms of the invention:—

Fig. 1 is an elevation partly in section of 35 one form of the invention.

Fig. 2 is a detail sectional elevation illustrating a mill in which one of the elements shown in Fig. 1 is dispensed with.

Figs. 3 and 4 are somewhat diagrammatic 40 detail sections employed in explaining the theory of operation of the invention.

Referring to Fig. 1 it will be seen that I have shown a conical mill comprising a rotatable drum 10 having an inlet trunnion 21, and bearing 12 therefor; a substantially 45 cone-shaped outlet portion 11 for the automatic classification of material according to size; an outlet opening 12 for the discharge of the material when it has been reduced to fines, i. e. particles of a predetermined size; and a bearing 13. Means, comprising a gear wheel 15 secured to the drum, are provided for rotating the drum and it will be understood that balls, pebbles or other suitable 50 grinding media (not shown) may be em-

ployed with the mill. If desirable, the drum 10 may be provided with suitable lining material or liners 14. Before proceeding with the description of the discharge end of the mill shown in Fig. 1 I shall describe outlet 60 means hereto employed by me.

Referring to Fig. 3 (in which parts corresponding to those illustrated in Fig. 1 are designated by the same reference numerals but with subscripts *a*), it will be seen that the conical outlet portion 11^a discharges, through the opening 12^a, into a trunnion 16^a having a substantially cylindrical bore. A mill of the type illustrated in Fig. 1, but provided with the outlet means shown in 70 Fig. 3, possesses marked advantages now clearly understood by those skilled in the art. Material to be disintegrated may be fed through the trunnion 11 into the drum 10, while the latter is rotating. It is there subjected to the disintegrating action of the grinding media. By virtue of the conical portion 11^a the material is automatically classified according to size and the fines, i. e. particles of a predetermined size, are discharged through the outlet trunnion 16^a. Though such a mill is extremely advantageous and efficient nevertheless it is susceptible to improvement. The cone-shaped portion 11^a, when rotated, impels the fines outwardly. The trunnion 16^a, being cylindrical, exerts no such force so that a retardation of the flow of fines occurs in such a trunnion. It is important that the fines be discharged from 75 mills of the type described quickly and as soon as possible after they have been reduced to predetermined size. Fines within the mill decrease the efficiency not only because they constitute dead weight and energy is wasted in rotating them, but also because 80 they cushion the impact of the grinding media upon the larger particles. In accordance with the present invention I provide means for accelerating the discharge of fines. One form of such means is somewhat 85 diagrammatically illustrated in Fig. 4 and may be explained as follows.

The conical outlet portion 11^b of the mill extends into the trunnion 16^b and is there joined by the smaller end of a diverging 100 spout member 17^b which also extends into said trunnion and is open at its larger end. It will be noted that the members 11^b and 17^b form a relatively convergent-divergent 105 outlet opening for the mill, the throat 12^b 110

being surrounded by the trunnion 16^b. In operation, the material is ground within the mill and automatically classified according to size in the outlet portion 11^b. The fines 5 pass through the throat 12^b and then drop automatically and quickly by gravity, down the inclined wall of the spout 17^b. The efficiency of this type of mill is thereby made a maximum.

10 Returning now to Fig. 1 it will be seen that the parts 11, 12, 13, 16 and 17 correspond to the parts 11^b, 12^b, 13^b, 16^b, 17^b illustrated in Fig. 4. The spout or discharge member 17 is shown as comprising an outer portion, adapted to be attached to or removed from the mill by virtue of the bolt and flange connection illustrated, and an inner member 18, forming a continuation of said outer portion. It will also be noted 15 that the member 18, constituting the inner end of the spout, is in the form of a liner 18.

If desirable the conical outlet portion of the mill may be provided with a cage 19 to prevent the discharge of the balls, pebbles or 20 other grinding media, with which the mill may be provided, but to permit the discharge of fines by the action of the conical outlet. While this cage may assume other forms I now prefer to employ one of the type illustrated 25 with an opening 20 at or adjacent its apex. A substantially cone shaped member 19, provided with lateral slits or perforations of such size as to differentiate between grinding media and fines, is shown secured 30 at its base to the apex portion of the conical outlet portion 11. The operation of the improved mill illustrated in Fig. 1 may now be summarized as follows.

The gear wheel is rotated to rotate the mill 40 and material is fed into the mill through the inlet trunnion 21. The material within the mill is subjected to disintegrating action and as it becomes reduced to predetermined size automatically passes through the throat 45 12 within the trunnion 16. If the cage 19 is employed the fines enter the same and drop through the openings thereof; the grinding media being retained although the mill is being forced. The fines, upon leaving the 50 cage 19 enter the discharge spout 17 and rapidly drop by gravity through the latter.

In accordance with the provisions of the patent statutes I have disclosed what I now consider a preferred form of the invention. 55 It will be understood that the structure illustrated may be modified in various respects

without departing from the scope of the appended claims. For example, if desired, the cage 19 may be dispensed with, such an arrangement being illustrated in Fig. 2. In 60 the last mentioned figure the shape of the liner 18^c is slightly different from that of the corresponding liner 18 shown in Fig. 1. Other modifications within the scope of the appended claims will occur to those skilled 65 in the art and, to avoid surplusage, I have omitted specific disclosure of such modifications.

What I claim is:—

1. In combination, a conical grinding mill 70 having a convergent-divergent outlet opening for automatically classifying material according to size and automatically discharging the same upon rotation of the mill, a cage within said outlet opening for preventing the discharge of grinding media, and a trunnion bearing for said mill surrounding the throat of said convergent-divergent outlet opening.

2. A conical grinding mill comprising in 80 combination, a trunnion and bearing therefor, a rotatable drum provided with a substantially cone-shaped outlet portion provided at its apex with a cage for preventing the discharge of grinding media, and a diverging spout extending into said trunnion and into which said drum discharges.

3. A conical grinding mill comprising in combination, a bearing, a rotatable drum having a substantially cone-shaped outlet 90 portion which extends into said bearing, and a diverging discharge spout extending into the opposite end of said bearing for receiving the discharge of said outlet portion.

4. A conical grinding mill comprising in 95 combination, a rotatable drum having a substantially cone-shaped outlet portion provided at its apex with a substantially cone-shaped cage for preventing the discharge of grinding media.

5. A conical grinding mill comprising in combination, a rotatable drum having a substantially cone-shaped outlet portion provided at its apex with a substantially cone-shaped cage for preventing the discharge of 105 grinding media, and a diverging discharge spout surrounding said cage to receive the discharge of fines therefrom.

In testimony whereof I hereto affix my signature.

HARRY W. HARDINGE.
